UNITED STATES PATENT OFFICE

MSTISLAV KULZINSKI, OF TALLINN, ESTHONIA, ASSIGNOR TO EESTI PATENDI AKTSIASELT, OF TALLINN, ESTHONIA

APPARATUS FOR DRY DISTILLATION

Application filed November 27, 1928, Serial No. 322,251, and in Estonia

I, MSTISLAV KULZINSKI, of 21, Toompuies-tee, Reval, Estonia, Engineer, do hereby declare the nature of this invention to be as follows:

5 In distillation furnaces, driers, kilns and similar ovens, where the treatment of the material is effected by way of injections and circulations of gas and vapour, there arise generally great difficulties in the conduction 10 of gas and vapours through the material placed on wagons. This is usually achieved in such manner, that along the side walls of the oven there are arranged sand packings running between the oven and the longitudi- 15 ninal sides of the wagon. These sand packings, however, are very often unsatisfactory and great care has to be taken in order to keep them in good condition. It is also difficult to achieve thereby sufficient packing be- 20 tween the front sides of the wagon. As a result of all these defects the working of all such ovens is bad and their efficiency low.

My invention relates to wagons and rails and has for its object to provide an im- 25 proved construction of wagons and rails, so as to remove the above referred to defects and to ensure a reliable and more complete (viz with but small losses) admission of the injected or circulated gas and vapours to the 30 material placed on such wagons.

In the accompanying drawing wherein an approved embodiment of the invention is illustrated

Figs. 1 and 2 are longitudinal sections 35 through a rail track and wagon constructed in accordance with the invention, Fig. 1 showing the opening of the wagon in registration with the furnace pipe and Fig. 2 showing the wagon slightly displaced there- 40 from;

Fig. 3 is an enlarged fragmentary detail of the recessed portion of one of the track rails showing the recess therein and the wagon wheel located in said recess;

Fig. 4 is a transverse sectional view 45 through the furnace, wagon and track rails;

Fig. 5 is a fragmentary plan view of a modification of the invention.

The wagon (Figs. 1, 2 and 4) consists of a 50 box (Q) provided with a double bottom.

The upper bottom (e) is made of network, perforated sheet metal, fire bars or the like and is permeable to gas. The other bottom (f) however is impermeable, but is provided with an opening (o) for the admission of the 55 gases and vapors, the said opening being preferably provided with a flange (b). The wagon is movable on rails (r), see Figure 4, through the furnace (M) while sufficient space (d)—Fig. 2—must remain between 60 the flange (b) and the tube (c) provided in the furnace and supplying the scavenging gases in order that the wagons may move freely. The rails arranged in the furnace are provided at suitable places with grooves (a) 65 Figs. 1, 2, 3 and 4 which are arranged in such a manner that all wheels of a wagon roll simultaneously into the said grooves and the wagon adjusts itself exactly above the corresponding tube (c) adapted for the ad- 70 mission of gas and vapors.

The grooves (a) in the rails must have such dimensions that the flange (b) bears with sufficient tightness against the edge of the tube (c) in the bottom of the wagon 75 when the latter descends. The intermediate space (d', Figs. 1 and 4) dependent on the dimensions of the groove in the rails (a) may be kept as small as desired so that even a complete mounting of the flange (b) on the 80 edge of the tube (c) is rendered possible, thereby ensuring a reliable admission of the injected and circulating gases and vapors to the material in the wagons without any loss. During the forward movement of the wagon, 85 the wheels (w) thereof move out of the groove (a), whereupon the wagon together with the flange (b) is lifted and there is formed again sufficient space (d, Fig. 2) be- 90 tween the tube (c) and the flange (b) for enabling the wagon to move freely to the next tube for the admission of gases and va- 95 pors.

A rail track is used in connection with this arrangement wherein the rails have the 95 known grooves (a). During the movement of the wagon, the wheels must pass during each new adjustment over the tubes (c) the rail grooves (a) without stopping i. e. they must overcome certain resistances during the 100

movement. In order to obviate this in connection with heavier wagons, two rail tracks may be employed as shown in Figure 5 of the accompanying drawing. The width of track 5 (r) of one pair of wheels (w) is greater than the width of track (r') of the other pair of wheels (w') and the power required for the forward movement of the heavier wagons will be less because the first pair of wheels 10 (w) must not then unnecessarily roll over grooves lying in its path as in connection with two rails before gliding into the grooves corresponding to the mounting of the flange (b) over the next tube (c). The supply of 15 the scavenging gases for one wagon may also eventually take place through several inlet pipes, in which case, the lower bottom of the wagon has a corresponding number of holes, as described above which are located during 20 the descent of the wagon on the corresponding sockets of the inlet pipes.

Having now particularly described and ascertained the nature of my said invention and in what manner the same is to be performed, I declare that what I claim is:

25 1. In combination, a furnace having gas and vapor pipes, rails in said furnace, a wagon including wheels movable on said rails and having a double bottom, the upper part 30 of the bottom being permeable to gas and the lower part thereof being solid and having an opening provided with a flange for the admission of injected or circulating vapors from the furnace pipes, said rails having recesses therein at such points that when 35 the supporting wheels of the wagon simultaneously move into the recesses the flanged opening of the wagon registers with and engages the furnace pipe, said recesses being of such depth as to limit descent of the flanged 40 opening to the approximate level of the furnace pipe and acting to effect elevation of the wagon when the latter is moved in either direction from a position of registration of 45 the flanged opening with the furnace pipe.

50 2. An arrangement as claimed in claim 1, characterized in that the wagon includes two wheeled axles and that four rails are provided, the wheels of one axle being arranged to move on the two inner rails and the wheels of the other axle on the two outer rails.

In testimony whereof I affix my signature.
M. KULZINSKI.
